UNITED STATES PATENT OFFICE.

JOHN WHITWORTH AND CHARLES RODERICK, OF WOODSTOCK, ILLINOIS, ASSIGNEES TO
SANITARY SCALE COMPANY, OF CHICAGO, ILLINOIS, A CORPORATION OF ILLINOIS.

SHIPPING CRATE.

Application filed March 19, 1923. Serial No. 625,958.

To all whom it may concern:

Be it known that we, JOHN WHITWORTH and CHARLES RODERICK, citizens of the United States, residing at Woodstock, in the county of McHenry and State of Illinois, have jointly invented certain new and useful Improvements in Shipping Crates, of which the following is a specification.

This invention relates to shipping crates, and has for one of its objects to provide a construction of shipping crate which will absorb shocks incident to dropping the crate and prevent transmission of such shocks to the contained goods, and a construction which will be effective particularly in preventing the development of strains transversely of the crated goods when the package or crate is dropped on either of its ends. Accordingly, one feature of the invention consists in providing a crate with a false bottom or crating bed so related thereto as to be in vertical bearing above the true bottom of the crate over but a limited area, and confining the bed upon the said bearing in a manner to afford a limited rocking movement of the bed upon its bearing, and thus permitting depression of that end of the bed and the attached article of merchandise which is over the end upon which the dropped crate alights, and thereby preventing direct transmission of the shock incident to the drop. Preferably, the bed is confined closely upon its bearing of limited area by means of cleats fitted snugly above the sides of the bed, and the said bearing in is developed through means of cushioning material so that the permitted depression of an end of the bed results from compression of the bearing, and absorption of shock is not only correspondingly increased but is dissipated as well in case the crate is dropped squarely upon its bottom rather than upon an end. Incidentally, confinement of the bed between its bearing and the cleats permits the bed with the crated goods to slide into or out of assembly with the bottom of the crate and such enclosing frame or walls as the bottom may carry.

Another object of the invention is to provide means for mounting an object to be crated upon the crating bed of the kind herein described, in a manner to resist vertical, horizontal, or tipping displacement of the object relatively to the bed, thereby

adapting the bed to serve as the sole sustaining and restraining means for the object, and render unnecessary the development of confining bearings between upper portions of the crate and the upper portion of the crated object, and thus permitting all parts of the object to partake of the tipping movements incident to rocking movements of the bed and preventing the development of strains transverse to the vertical dimension of the object, which would be unavoidable with close confinement of the upper portion of the object in the upper portion of the crate. Accordingly, another feature of the invention consists in firmly anchoring the crated object to the crating bed in a manner to resist vertical, horizontal, or tipping movements between the base of the object and the bed, and defining the position of the object in the crate entirely by confining means cooperating directly upon the bed.

Still another object is to provide improved means for transmitting the tipping movements of the upper portion of the object directly to the bed without imposing stresses upon the base of the object, or upstanding portions thereof, and, accordingly, another feature of the invention consists in introducing struts or stays extending from the bed directly to the upper portion of the crated object, and preferably, in addition thereto, stays extending from an intermediate portion of the object indirectly to the bed, as, for instance, to a clamping beam through which the base of the crated object is secured to the bed.

In order that the invention may be fully understood, an illustrative embodiment thereof will be described in detail in connection with the accompanying drawings, which show a shipping crate designed particularly for the protection of an object, such as a weighing scale composed of a base, an upstanding column upon the base, and a chart housing or head supported on the column. In said drawings—

Figure 1 is a front elevation of the crated package with the omission of the bottom rail that is employed to prevent the crating bed from sliding out of the crate, and omitting also the front wall of the housing that will ordinarily be embodied with the crate to prevent access to the goods from without; and

Figure 2 is a side elevation with the side wall of the crate and housing as well as the near confining cleat omitted.

- 1 represents the bottom of a crate which 5 may have mounted upon it any suitable construction of sides 2 extending upwardly the necessary distance to protect the upper portion of the goods to be crated, and a top 10 3 supported upon said sides. 4 represents a crating bed which may be assembled from lumber of conveniently available dimensions, and preferably including battens 5, which bed is supported upon the bottom 1 through a bearing 6 of suitable cushioning 15 material, preferably rubber, and conveniently provided in subdivided units in the form of separate cushions, as shown in Figure 2; and this resilient bearing, while preferably positioned near the side margins 20 of the bed 4, as shown in Figure 1, is restricted in area very materially in the longitudinal direction of the bed, as shown in Figure 2, so as to leave extended overhanging portions 4^a, 4^b of the bed 4 which are 25 unsupported and adapted to move downward rather than be suddenly arrested when the crate is dropped upon either of its ends 1^a or 1^b, thus avoiding transmission of the impact directly to the end of the crated object, and avoiding serious bending movement and consequent strains transversely of the base of an object that may be mounted upon said bed. For instance, let it be supposed that a weighing scale comprising, in general, 30 a base A, upstanding column B, and a chart housing or head C, is resting upon the bed 4 of the crate, and in handling the crate during transport it is permitted to drop upon its end 1^a. If the bed 4 were resting 35 immediately upon the bottom 1, the shock of this drop would be transmitted directly to the corresponding end of the base A, and this in turn acting against the resistance offered by the inertia of the whole mass B, 40 C, will develop a serious bending strain in an intermediate portion of the base A and tend to crack the base, if a casting, or chip off the enamel therefrom if it were finished in such material. By having the bearing 6 45 restricted in area so that the end 4^a of the bed has a substantial overhang without vertical support, the said end 4^a will be relieved of the shock of the drop, the whole bed with the scale or other object supported thereon can execute a slight tipping action, 50 and the shock will be absorbed.
- In order to confine the bed 4 upon its limited area of bearing 6, cleats 7 are placed over the side margins of the bed, as 55 shown in Figure 2, these cleats extending to the extreme front and rear ends of the bed, as suggested in Figure 2, and the bearing 6 is made of resilient material so that in the case instanced when the crate is dropped upon its front end 1^a, the confinement of

the rear end 4^b of the bed by the cleat 7 develops a fulcrum at that point and causes compression of the bearing 6 in a degree proportionate to the depression of the forward end of the bed. Similar action and 70 distribution of stresses follows the dropping of the crate upon its rear end, although, perhaps, in a degree less than when dropped upon the front end because of the location of the main vertical dimension of the scale 75 nearer to the rear end. Obviously, with the resilient nature of the bearing member 6, shocks incident to dropping the crate squarely upon its bottom will not be injuriously transmitted to the scale because of the 80 location of the bearing with relation to the center of gravity of the scale.

In order to avoid injury to the upper portion of a scale by developing bearing between it and the upper portion of the crate, the base A of the scale is firmly clamped to the bed 4 of the crate through means of a beam 8 and bolts 9 passing through the beam and bed, said beam resting upon a rigid portion of the scale, such, for instance, as a so-called shipping spider 10 which is commonly used to rigidly position the levers or other moving parts of the scale mechanism during shipment; and the base A is secured against horizontal displacement 95 upon the bed by suitable means, such, for instance, as blocks 11, 12, and 12^a, located, respectively, at the front, back, and sides, and in this way the scale is forced to partake of all movements of the bed as well as 100 prevented from any movement independently of the bed.

With the described method of supporting the bed 4 upon the bearing 6 and confining them in position by cleats 7, it is possible, as will be appreciated by inspecting Figure 1, to slide the bed 4 into and out of position between the bearing 6 and cleats 7, and this permits the scale or other object to be mounted upon and removed from the bed 110 while the bed is out of the crate. Preferably an abutting plate 11^a, bridged across the rear ends of the cleats 7, is located to arrest or assist in arresting the inward movement of the object and bed. 115

To absorb stresses that might otherwise be imposed upon the upstanding portion of the crated scale, and take up any tipping movement of the upper portion of the scale relatively to its base, struts 13 are extended from the beam 8 diagonally rearward and upward to a substantial yoke 14, the two members 14^a and 14^b of which are clamped upon the upper portion of the column B, and these struts 13 act both under compression and tension in staying the upstanding portion of the crated object. 120

In order to stay the upper portion of the crated article, laterally inclined struts 15 are fitted snugly between the bed 4 (prefer- 125 130

ably indirectly and through the medium of the staying blocks 12^a) and the underside of the head or chart housing C of the scale; and these struts 15 may be secured by nails or 5 equivalent means 16 to the yoke 14.

In addition to the beam 8 drawn downward upon the intermediate portion of the base A upon which it bears indirectly through the medium of the spider 10, there 10 is preferably a shorter beam 17 drawn downwardly by screws 18 upon a rear portion of the base A in close relation to the column B.

From the foregoing description it will be seen that the object to be crated is mounted 15 firmly upon the bed and held there against lateral, vertical, or tipping displacements; that the crated object is confined against lateral, vertical, and tipping displacement of the crate entirely by means of said bed; 20 and that the bed is held in the crate resiliently both vertically and in tipping directions, and can receive no upwardly transmitted shock from the bottom of the crate except through the medium of the bearing 25 of restricted area beneath the intermediate portion of the scale or crated object, and only in a very slight degree through this bearing because of its inherent cushioning nature.

30 I claim:

1. In a shipping crate for objects having bases upon which they stand when in use; a crate bottom, a bed adapted to the crated object and a bearing between the bottom and bed having a horizontal dimension materially less than that of the crated object base and positioned beneath the bed to leave the crated object supported upon essentially a rocking bearing and with a substantial overhanging portion, beyond said bearing, de- 35 pressible under shocks directed upwardly beneath said overhanging portion.

2. In a shipping crate for objects having bases upon which they stand when in use; a crate bottom, a bed adapted to the crated object and a bearing between the bottom and bed having a horizontal dimension materially less than that of the crated object base and positioned beneath the bed to leave the crated object supported upon essentially a rocking bearing and with a substantial overhanging portion, beyond said bearing, de- 40 pressible under shocks directed upwardly beneath said overhanging portion, means being provided for limiting lift of the portion of the object-base on the opposite side of said bearing from said overhanging portion.

3. In a shipping crate for objects having bases upon which they stand when in use; a 45 crate bottom, a bed adapted to the crated object and a bearing between the bottom and bed having a horizontal dimension materially less than that of the crated object base and positioned beneath the bed to leave the crated object supported upon essentially a

rocking bearing and with substantial overhanging portions on opposite sides of said bearing, de-pressible under shocks directed upwardly beneath said overhanging portions. 50

4. In a shipping crate for objects having bases upon which they stand when in use; a crate bottom, a bed adapted to the crated object and a bearing between the bottom and bed having a horizontal dimension materially less than that of the crated object base and positioned beneath the bed to leave the crated object supported upon essentially a rocking bearing and with substantial overhanging portions on opposite sides of said bearing, de-pressible under shocks directed upwardly beneath said overhanging portions; means being provided for limiting upward movement of either of said overhanging portions as the other is depressed. 55

5. In a shipping crate, a bed adapted to receive an object to be crated, a bottom member for supporting said bed, and a bearing between said bed and bottom support, restricted in sustaining area to an intermediate 60 portion of the bed, and leaving portions of said bed projecting on opposite sides of said bearing free from support and de-pressible; means being provided to limit the raising of the bed from its said bearing; said bearing being constructed of cushioning material that is compressed under the depression of an overhanging end. 65

6. In a shipping crate, a crate-bottom, a bed adapted to receive an object to be crated, 70 and having means for securing such object against tipping on said bed, and a bearing between the crate-bottom and bed restricted horizontally to a dimension materially less than the corresponding dimension of the bed and positioned to leave the bed supported upon, essentially, a rocking bearing and with an overhanging portion of the bed beyond such bearing unsupported and de-pressible under shocks directed upwardly beneath 75 the same. 80

7. In a shipping crate, a bed adapted to receive an object to be crated, a bottom support for said bed restricted in area to leave a substantial portion of the bed extending beyond the bearing unsupported and adapted to be depressed toward the bottom support, and means being provided for fixing to said bed an object to be crated and holding it against tipping thereon; said last-named means comprising a base clamp for holding the lower portion of the object to the bed and a strut bracing the upper portion of said object relatively to the bed. 85

8. In a shipping crate, a bed adapted to receive an object to be crated, a bottom support for said bed restricted in area to leave a substantial portion of the bed extending beyond the bearing unsupported and adapted to be depressed toward the bottom sup- 90

port, and means being provided for fixing to said bed an object to be crated and holding it against tipping thereon; said last-named means comprising a clamping beam for binding to the bed the lower portion of the object to be crated and a strut inclining from said beam to an upper portion of said object.

9. In a shipping crate, a bed adapted to receive an object to be crated, a bottom support for said bed restricted in area to leave a substantial portion of the bed extending beyond the bearing unsupported and adapted to be depressed toward the bottom support, and means being provided for fixing to said bed an object to be crated and holding it against tipping thereon; said last-named means comprising a clamping beam for binding to the bed the lower portion of the object to be crated, a strut inclining from said beam to an upper portion of said object, and a yoke through which the upper end of said strut is secured to the object.

10. In a shipping crate, a bed, a supporting base upon which said bed is mounted with limited rocking movement, means for securing to said bed the lower portion of an object to be crated, a yoke for embracing the upper portion of said object, and a pair of struts extending diagonally upward to the respective ends of said yoke.

11. In a shipping crate, a supporting base, a bed mounted on said base with limited rocking movement, means for clamping to said bed an object to be shipped, and bracing struts extending from the bed upwardly and adapted to enter into bearing with the upper portion of said object.

12. A shipping package, comprising a

bottom support, a bed having a limited area bearing upon said support and adapted to rock relatively thereto, a scale comprising a base portion and an upstanding portion lying upon said bed, a clamp for securing the base portion of the scale to said bed, and side braces extending from said bed upwardly and inwardly to and in bearing against said upstanding portion.

13. A shipping package, comprising a bottom support, a bed having a limited area bearing upon said support and adapted to rock relatively thereto, a scale comprising a base portion and an upstanding portion lying upon said bed, a clamp for securing the base portion of the scale to said bed, and side braces extending from said bed upwardly and inwardly to and in bearing against said upstanding portion; the upstanding portion of the scale being free from bearing against the crate.

14. In a shipping package, a bottom support, limited area bearings upon said bottom support, a bed upon said bearings and having a limited rocking movement relatively to said bottom support, a scale comprising a horizontal base portion and an upstanding column lying upon said bed, means clamping the base portion of the scale to said bed, side braces extending from the bed at the sides of the upstanding column and inwardly to and in bearing upon said upstanding column, and a strut extending from the base clamping means rearwardly and upwardly to and connected with the upper part of said column.

Signed at Woodstock, McHenry County, Illinois, this eighth day of March, 1923.

JOHN WHITWORTH.
CHARLES RODERICK.
